BLOWOUT PREVENTER AND TUBING HEAD
FOR PUMPING WELLSGlenn L. Cardwell, Long Beach, Calif., assignor
to Signal Oil and Gas Company, Los Angeles,
Calif., a corporation of Delaware

Application January 12, 1946, Serial No. 640,890

9 Claims. (Cl. 166—15)

1

This invention relates to a tubing head for pumping wells, and particularly to blowout preventers for such pumping wells.

A conventional manner for pumping oil wells is by means of a reciprocating pump positioned at the bottom of a string of tubing suspended in the well. The piston of the pump is reciprocated by a string of rods which is positioned in the tubing and projects through the upper end of the tubing. A packing is positioned at the end of the tubing and the rods project through the packing and are connected to and reciprocated by an oscillating beam called the "walking beam." The portion of the rod projecting through the packing and reciprocated therein is called the "polish rod." It is connected to the walking beam by a clamp.

Quite frequently, and sufficiently frequent to constitute a hazard to oil well production, the polish rod, due to fatigue failure, breaks off at the clamp and the rods and pump fall into the well through the packing. This opens the tubing to atmosphere. In most wells, other than so-called stripper wells, there is enough gas pressure to spew the oil and gas through the open tube and packing. This covers the surrounding territory with oil and constitutes a fire hazard.

I have devised a blowout preventer which automatically closes the tubing when such failure of the polish rod occurs.

My invention will be further described in connection with the drawings, in which:

Fig. 1 is an assembly, partly in section, of a tubing head employing my invention;

Fig. 2 is a vertical sectional view of the blowout preventer with the polish rod removed but with the plug in its retracted position as in operation in Fig. 1;

Fig. 3 is a view similar to Fig. 2 but with the plug in the shut-off position; and

Fig. 4 is a sectional view taken on the line 4—4 of Fig. 3.

The well tubing 2 is mounted on a conventional tubing hanger 1 and connected to flow valve 3. The tubing is connected by means of a collar 4 to the blowout preventer 5.

The blowout preventer has a central bore 6 large enough in diameter to pass the polish rod 25 and a cross bore 7 of greater diameter than said central bore into which is screwed the retainer 8. The cross bore 7 intercepts the central bore 6. The inner diameter of the retainer is substantially equal to that of the bore 7 and is greater in length than the diameter of the central bore 6. A second bore 10 is positioned in

2

the wall of the blowout preventer 5 diametrically opposed and coaxial with the bore 7. A removable plug 11, to act as a casing head closure, is positioned in the bore 10. Bore 10 terminates in an enlarged cylindrical recess or counterbore 9. The bores 9 and 7 are coaxial and substantially equal in diameter. The walls of the blowout preventer are chamfered at 12 at a radius of curvature substantially equal to the radius of the plug 13 to permit of a sliding fit of 13 in the bores 9 and 7. The plug 13 is also chamfered at 15 to give a polish rod receiving groove in the face of said plug preferably at a radius of curvature equal to the radius of the polish rod 25 and is held back by the polish rod which slides in the plug 13. The plug 13 is bored out at 14. A spring retaining chamber 8 is screwed into the bore 7. A spring 18 fits inside the retainer 8 and the bore 14 and rests in the recess 17. The length 20 of the plug is such that when in the shut-off position, shown in Fig. 3, the plug rests in bore 9 and in the bore 7.

Mounted in chamber 19 is a packing means. One suitable form is shown in Fig. 1. The packing is mounted by means of a ring 20 screwed into 19. The polish rod packing 21 is placed at 19. The compression ring 22 carries a bearing sleeve 23 forming a sliding fit with the polish rod 25. An annular disc 24 is screwed into 20. The polish rod 25 extends above the assembly and is carried on hanger 27 by means of a clamp 26. Hangers are mounted in the walking beam 28. This mounting is conventional.

Should the rods break below the hanger 26 and above the top of 24, the rods 25 will drop through the assembly and into the tube 2 so that the top of the rods will be below 13. There being no rod to hold the plug back, the spring which is under compression will snap the plug into position as shown in Fig. 3 the plug 9 being of substantially the same diameter as the bores 7 and 9 and making a sliding fit therewith on both sides of the central bore, which makes a circumferential seal in these bores thus shutting off the central bore. Should the break come below the shut-off plug, the walking beam on its up-stroke will lift the polish rod out of the tubing head assembly and the plug, acting as a casing head closure member, will shut off in the described manner. In either case the pressure in the tubing will be maintained and no loss of oil over the top of the tubing head will occur.

To reset the blowout preventer, the chamber 8 is unscrewed and the spring is removed. By un-

screwing plug 14, the plug 13 may be pushed back into open starting position.

The above blowout preventer is thus composed of a closure member held in open position by the polish rod which passes through a bore in the blowout preventer, and the closure member moves to close the bore when the polish rod is removed from the bore which is then closed by the movable member. The closure member is thus urged to a closed position positively and acts to shut off the flow of fluid in the well when the polish rod is removed from the bore.

Various modifications will suggest themselves to those skilled in the art.

While I have described a particular embodiment of my invention for the purpose of illustration, it should be understood that various modifications and adaptations thereof may be made within the spirit of the invention as set forth in the appended claims.

I claim:

1. A blowout preventer member for a pumping well, comprising a central bore through said casing head adapted to receive a pump polish rod, an unobstructed cross bore of greater diameter than said central bore intercepting said central bore, said cross bore extending on both sides of said central bore, a plug, of substantially the diameter of said cross bore and of greater length than the diameter of said central bore, in said cross bore, said cross bore being closed at both ends thereof, and yieldable means for normally urging said plug into closed position across said central bore said plug extending into said cross bore on both sides of said central bore and making a circumferential seal around said plug in said cross bore on both sides of said central bore to close the same when a pump polish rod is not positioned in said central bore, and a separate polish rod packing means associated with said central bore.

2. A blowout preventer for a pumping well, comprising a central bore through said blowout preventer adapted to receive a pump polish rod, an unobstructed cross bore of greater diameter than said central bore intercepting said central bore, said cross bore unobstructedly extending on both sides of said central bore, a plug of substantially the diameter of said cross bore and of greater length than the diameter of said central bore, slidably positioned in said cross bore, said cross bore being closed at both ends thereof, a spring, a spring and plug receiving chamber connected to said cross bore, said spring being positioned behind said plug to normally urge said plug into closed position in said cross bore, said plug being positioned on both sides of said central bore and across said central bore said plug making a circumferential seal around said plug in said cross bore on both sides of said central bore and a polish rod receiving groove in the face of said plug to close the same when a pump polish rod is not positioned in said bore, and a separate polish rod packing means associated with said central bore.

3. In combination, a tubing for a pumping well, a blowout preventer mounted on said tubing, a central bore through said blowout preventer, a polish rod reciprocably mounted in said casing head, a closure member for said central bore positioned in said blowout preventer in sliding contact with said polish rod, and means for forcing said closure member against said polish rod when said polish rod is mounted in said casing head, said means being sufficient to force said closure

member into closed position across said central bore to shut said central bore off when said polish rod is not in position in said central bore.

4. A blowout preventer assembly for oil well tubing of a pumping well, comprising a tubing for said well including a fluid discharge conduit connected to said tubing, a casing head for said tubing positioned above said fluid discharge conduit, a central bore in said casing head, a packing on said blowout preventer, an oil well polish rod reciprocably positioned in said packing and said central bore, a cross bore in said blowout preventer positioned in said casing head and intersecting said central bore and extending on both sides of said central bore, a closure member positioned in said cross bore and adapted to extend across said central bore and into said cross bore on each side of said central bore when said polish rod is not in said central bore, said polish rod, upon positioning in said central bore, holding said closure member in said cross bore on one side of said central bore, and means positioned in said casing head to force said closure member against said polish rod, said means being sufficient to force said closure member into closed position when said polish rod is not in position in said central bore.

5. In combination, a tubing for a pumping well, a blowout preventer mounted on said tubing, a central bore through said blowout preventer, a cross bore in said casing head intersecting said central bore and extending on both sides of said central bore, a polish rod reciprocably mounted in said central bore, a plug positioned in said cross bore and slidably fitting in said cross bore and in sliding contact with said polish rod, a spring in said cross bore operatively engaging said plug to hold said plug in sliding contact with said polish rod, said plug fitting across said central bore and into said cross bore on both sides of said central bore when said polish rod is out of contact with said plug.

6. In combination, a blowout preventer for tubing for a pumping well, a central bore in said tubing, a cross bore intersecting said central bore and extending on both sides of said central bore, said cross bore being of greater diameter than said central bore, said central bore being chamfered at said intersection to a diameter substantially equal to the diameter of said cross bore, a plug slidably positioned in said cross bore of diameter substantially equal to the diameter of said cross bore and of length greater than the diameter of said central bore, whereby said plug extends on both sides of said central bore into said cross bore on both sides of said central bore, and a resilient means operatively engaging said plug to resiliently position said plug in said closed position said plug making a circumferential seal in said cross bore on both sides of said cross bore.

7. In combination, a tubing for a pumping well, a blowout preventer mounted in said tubing, said blowout preventer comprising a central bore, a cross bore of greater diameter than said central bore and intersecting said central bore, said cross bore extending on both sides of said central bore, a polish rod reciprocably mounted in said central bore, a plug positioned in said cross bore, a spring in said cross bore operatively engaging said plug to resiliently hold said plug in sliding engagement with said polish rod, the diameter of said plug being substantially equal to the diameter of said cross bore and the length of

the plug being substantially greater than the diameter of said central bore.

8. In combination, a tubing for a pumping well, a blowout preventer, said blowout preventer comprising a cross bore of greater diameter than said central bore and intersecting said central bore, said cross bore extending across on both sides of said central bore, a polish rod reciprocably mounted in said blowout preventer polish rod packer and said central bore, a plug positioned in said cross bore, a spring in said cross bore operatively engaging said plug to resiliently hold said plug in sliding engagement with said polish rod, the diameter of said plug being substantially equal to the diameter of said cross bore and the length of the plug being substantially greater than the diameter of said central bore a polish rod receiving groove in the face of said plug, said plug making a circumferential seal in said cross bore on both sides of said central bore. 15 20 25

9. In combination, a tubing for a pumping well, a blowout preventer mounted on said tubing, a bore through said blowout preventer, a polish rod reciprocally mounted in said bore, a closure member for said bore, means continuously urging said

closure member towards closed position in said bore and means including said polish rod to hold said closure member in open position when said polish rod is in said bore, whereby said urging means moves said closure member to closed position upon removal of said polish rod from said bore.
